FILLING NECK AND ANTITHEFT ASSEMBLY
FOR GAS TANKS

Phineas T. Mann, Springfield, Ohio

Application January 21, 1936, Serial No. 60,101

1 Claim. (Cl. 220—86)

This invention relates broadly to gas tanks and more particularly to tanks forming part of an automobile equipment for carrying gasoline.

The invention is particularly concerned with 5 means for preventing theft, by siphoning, or otherwise from such tanks.

Briefly the invention consists in an assembly of 10 parts which may be readily applied to the gas tank and which includes a filling neck for the tank together with means for effectively preventing 15 the siphoning of gasoline from the tank through said neck.

The invention together with its objects and 20 advantages will be best understood from a study 15 of the following description taken in connection with the accompanying drawings wherein:

Figure 1 is an elevational view of the neck and 25 anti-theft assembly, and illustrating an application 20 of the same to a tank, a portion of which is shown in section.

Figure 2 is a longitudinal sectional view taken 30 substantially on line 2—2 of Figure 1.

Figure 3 is a top plan view with the cap removed.

Figure 4 is a fragmentary elevational view of 35 the upper portion of the anti-theft cylinder.

Figure 5 is a top plan view of an anti-splash 40 collar and

Figure 6 is a side elevational view thereof.

Referring more in detail to the drawings it will 45 be seen that in accordance with the present invention, and in the preferred embodiment thereof, there is provided a cylindrical filling neck 5 for use with a gasoline tank a portion of which 50 is shown in the drawings and indicated by the reference numeral 6.

At its base or lower end the neck 5 is provided 55 with an outstanding annular attaching flange 7 formed with slots 8.

The neck 5 is also externally threaded and is 60 adapted to have screwed thereon as at 9 a suitable closure cap 10.

Further the invention comprises an anti-theft 65 cylinder 11 which at its upper edge has formed integral therewith upstanding lugs 12 having reduced terminals to provide bendable fingers 13 and shoulders 14 at the junction of the fingers 13 with the lugs 12.

Further the invention comprises an anti-splash 70 cylinder 15 which has projecting from its upper edge spaced flanges 16 formed with slots 17.

Further in accordance with the present invention 75 the top of the gasoline tank 6 is provided with a filling opening 20 and inwardly from said

opening the top of the tank is provided with slots 19.

In assembling the parts herein described in detail the base flange 7 of the neck 5 rests on the top of the tank 6 with the slots 8 in the flange 5 in registry with the slots 19 in the top of the tank 6.

The splash cylinder 15 is disposed concentric to the opening 20 and has its flanges 16 disposed against the inner side of the top of the tank with 10 the openings 17 in the flanges in registry with the openings 19.

The anti-theft cylinder 11 is disposed within the tank and the fingers 13 are passed upwardly through the aligned slots or openings 8, 19 and 17 15 as shown in Figure 2 and then clinched as also shown in Figure 2 to hold the parts in the assembled relation shown in said figure. In this connection it will be understood that the assemblage will take place during the construction of the 20 tank 6.

With the parts assembled as shown in Figure 2 it will be noted that shoulders 14 together with the lugs 12 will serve to space the upper edge of the anti-theft cylinder downwardly from the top 25 of the tank 6 so that the gasoline entering the cylinder 11 will overflow through the space between the upper edge of the cylinder 11 and the top of the tank 6 into the tank for filling the same.

The manner of filling the tank is thought to be 30 obvious, the gasoline being introduced through the neck 15 and the anti-splash cylinder 15 into the cylinder 11 to overflow the cylinder into the tank, cylinder 15 serving not only to prevent splashing of the fluid as it is being introduced into 35 the gasoline tank, but said cylinder will also serve to effectively prevent the passage of any element into the tank 6 as might be effectually used for siphoning the gasoline contents from the tank.

It is understood that after the fingers 13 have 40 been clinched as shown in Figure 2 said fingers may be riveted, spot-welded or otherwise secured so as to prevent any dismantling of the parts.

Having thus described the invention, what is 45 claimed as new is:

In combination with a gasoline tank having a wall provided with a filling opening and a series of slots disposed about said opening and spaced inwardly from the edge thereof; a filling neck having a base flange resting on the outer face of 50 said wall, and having openings in said flange registering with the first named openings, and an anti-theft cylinder disposed within said tank and having an open end, and also having lugs projecting longitudinally from the peripheral 55

wall of said anti-theft cylinder at the open end thereof, said lugs having reduced ends extending through the aforementioned openings in the tank wall and flange of said neck and clinched to secure said neck and anti-theft cylinder in fixed position relative to said wall, with said lugs serving to space the open end of the anti-theft cylinder from said tank wall, an anti-splash, rela-

tively short cylinder disposed concentric to said filling opening and provided at one end with outstanding flanges provided with slots registering with the first named openings and through which said slots the aforementioned lugs also extend for securing said anti-splash cylinder in fixed position relative to the aforementioned parts. 5
